UNITED STATES PATENT OFFICE.

GENIO S. PARKER, OF DEEP RIVER, CONNECTICUT.

BURIAL-CASKET.

SPECIFICATION forming part of Letters Patent No. 356,660, dated January 25, 1887.

Application filed June 2, 1886. Serial No. 203,894. (No model.)

To all whom it may concern:

Be it known that I, GENIO S. PARKER, a citizen of the United States, residing at Deep River, in the county of Middlesex and State 5 of Connecticut, have invented certain new and useful Improvements in Composition Cases for Coffins and Caskets; and I do hereby declare that the following is a full, clear, and exact description of the same, reference being 10 had to the annexed drawings, making a part of this specification, and to the letters and figures of reference marked thereon.

Figure 1 of the drawings is a perspective view of a grave-casket case constructed in accordance with my invention, showing one of the lid-sections removed; Fig. 2, a longitudinal central section; Fig. 3, a transverse section; and Fig. 4 a detail view, in perspective, of one of the side sections of the casket-case.

20 The present invention has relation to that class of casket-cases formed of sections having their joining edges rabbeted, so that when placed together a tight joint will be formed between the several sections.

25 The object of the invention is to improve the above class of cases, whereby strength, durability, and lightness is obtained; and it consists of the details of construction, substantially as shown in the drawings and hereinafter described and claimed.

In the accompanying drawings, A B represent the side sections of the casket-case, having their outer ends or edges rabbeted, as shown at *a*, for fitting thereto the sections C, 35 which form the ends of the case, the lower edges of said sections resting on the supporting-flanges *b* of the side section. These flanges extend inwardly, and not only form supports for the ends of the casket-case, but present a 40 wide bearing-surface to prevent it from sinking in the ground.

The top of the case is made in two or more sections, D, their meeting edges being rabbeted, as shown at *c*, to form a tight joint between them, and are provided with strengthening-webs *d* upon their under sides, which form braces for said section to increase the strength and durability of the top or lid of the case, in order to resist the weight and pressure of the earth when the grave is being 50 filled. This strengthening-web in this class of casket-cases, where they are made of clay or a composition, is considered of importance, as it prevents the cover or lid from injury by any great weight placed thereon. The inwardly-extending flange, to support the ends, in place of making a complete bottom to the case, also has its advantages, as it dispenses with the necessity of an additional section for the bottom, which was usually made independent of the side section, thereby decreasing the cost of manufacture by the peculiar construction of the side section, and avoiding the necessity of making the side sections and bottom in one piece.

Having now fully described my invention, what I claim as new, and desire to secure by Letters Patent, is—

In a grave-casket case the sides thereof formed of two or more rabbeted sections having inwardly-extending supporting-flanges, in combination with the end sections and the top or lid formed of rabbeted sections having braces or webs upon their under sides, substantially as and for the purpose set forth.

In testimony that I claim the above I have hereunto subscribed my name in the presence of two witnesses.

GENIO S. PARKER.
